UNITED STATES PATENT OFFICE.

ASHER O. SINKS, OF PORTLAND, OREGON.

COMBINATION ROBE-CARRIER AND TABLE.

1,260,467.

Specification of Letters Patent. Patented Mar. 26, 1918.

Application filed April 27, 1917. Serial No. 164,874.

To all whom it may concern:

Be it known that I, ASHER O. SINKS, residing at Portland, in the county of Multnomah and State of Oregon, have invented 5 certain new and useful Improvements in Combination Robe-Carriers and Tables, of which the following is a specification.

My invention relates to certain new and useful improvements in devices for containing robes and other articles on automobiles in such manner that theft of the same is prevented and in addition thereto the invention has for its object to provide a structure which will not only have the useful function 10 of a container or robe carrier and protector but will also serve as a table whereby the occupants of an automobile may use the same as a luncheon table or for any other purposes for which a table is usually employed.

In its general nature, the invention consists of a box-like receptacle adapted to be secured to the automobile, preferably to the back of the front seat, by hidden fastenings, 25 the receptacle having a tiltable front which is adapted to swing forwardly and form a brace for a tray which is designed to be telescoped into the receptacle when the receptacle is closed and which is designed to be held horizontally on the receptacle and its swung open front to serve as a support for a foldable table top, the table top being designed to fit within the tray and be wrapped up in the robe or robes so as to 30 form a compact mass that will occupy the space within the tray to a sufficient extent to prevent movement around in the tray when the receptacle is closed up and thus deaden or prevent noise and rattling.

40 In its more detailed nature, the invention includes those novel features of construction, combination and arrangement of parts, all of which will be first fully described, then be specifically pointed out in the appended 45 claims and illustrated in the accompanying drawings, in which:

Figure 1 is a perspective view of the invention showing the receptacle open and the tray brought into the horizontal position 50 ready to receive the table top, the top being shown adjacently in perspective wrapped in the blanket.

Fig. 2 is a perspective view of the invention with the receptacle closed and locked.

55 Fig. 3 is a vertical cross section of the parts showing the table top in place, the

section being taken substantially on the line 3-3 of Fig. 5.

Fig. 4 is a cross section of the parts showing the receptacle closed, the folded table 60 top and robes being omitted.

Fig. 5 is a perspective view similar to Fig. 1 with the table top in place.

Fig. 6 is a view similar to Fig. 4 showing the tiltable table top and the robes in place 65 and illustrating how they occupy the space in the receptacle to prevent moving around and thus eliminate noise.

Fig. 7 is a detail perspective view of the hinged latch engaging finger that co-operates with the table top latch for holding the 70 table top in place.

Fig. 8 is a detail perspective view showing a portion of the table top with the table 75 top latch engaging the holding finger.

Fig. 9 is a detail section of a portion of the invention.

In the drawings, in which like numerals and letters of reference indicate like parts in all of the figures, 1 represents the back 80 of the receptacle which is preferably secured to the back of the front seat by fastenings 43 that are accessible only from the inside of the receptacle, the receptacle including the side walls 2, the bottom 3 and 85 the top flange 9. 10 designates hooks located under the top flange 9 of the receptacle and adapted to engage over the rod 24 of the hinged front or top member 20 of the tray when the parts are as shown in Figs. 90 2 and 4, the said member 20 having removed portions 25 to permit the hooks 10 to project through the same; the hooks 10 also function to project through the spaces 48 in the hinged flap 47 that is hinged at 95 45 to the inner or lower end of the tray 14 to engage with the same, while the tray is in the horizontal position shown in Fig. 3, the hooks 10 engaging the rod 24 when the tray is in the position shown in Fig. 4. 100

11 is the front of the receptacle which is provided with sides 46 that fit within the confines of the sides 2, the front 11 being hinged at 12 to the bottom 3 of the flange portion of the receptacle and having lugs 8 105 which engage with triangular swinging members 5 that are pivoted at 6 to the sides 2 of the receptacle, the sides 2 having slots 7 to permit the pins 8 to pass, the slots 7 being guarded by plates 4, as best indicated 110 in Figs. 1 and 3 of the drawings.

13 designates slots near the upper end of

the front 11 which are adapted to receive the ends of the hooks 17 that project through the slots 16 in the wall 14 of the tray, the hooks 17 being hinged at 18 to the sides of 5 the tray to fall to their hooking position by gravity. 19 designates the outer or top flange of the tray which is bent inwardly to guard the hinge member 20 against engagement by any contents of the tray, the hinge 10 member 20 being of L shape in cross section and having ears 22 through which it is hinged at 23 to the tray member and forms the operating member by which the latching and unlatching of the parts is effected. It 15 also serves as a closure for the top end of the receptacle when the parts are in the position shown in Fig. 2 and to this end, the member 20 has end flanges 20^a as well as the front portion 21 and the top or outer portion, as shown. When the parts are in the 20 closed position, as shown in Fig. 2, the member 20 lies under the top flange 9 of the receptacle 1.

In order to lock the receptacle in the closed 25 position the hinged operating member 20—21 has a guide 26 in which a latch bar 27 is slidable, the latch bar 27 being adapted to engage a lock 28 and be locked in the position shown in Fig. 4.

30 29 designates levers fulcrumed at 30 to the sides of the tray, one end of each lever 29 carrying latch pins 31 which project through apertures 49 in the end or bottom wall 15 of the tray and are designed to engage holes 34 in the wall of the receptacle 35 when the parts are positioned as shown in Figs. 1 and 3, but which project through holes 44 in the bottom 3 of the receptacle when the parts are positioned as indicated 40 in Figs. 2 and 4. The other ends of the levers 29 are connected by links 32 to pins 33 on the ears of the operating member 20—21.

35 designates the table top which is composed of two members hinged together at 36 and adapted to be folded over flatwise on each other to be wrapped in the blanket 50 and thus form not only a holder or core-like former for the blanket 50 but also be 45 protected by the blanket from rattling around in the tray when the parts are in the carrying position shown, for instance, in Fig. 6.

The hinged operating member carries a 50 rod 24 in the edges of the wall 20, a portion of which wall is cut away to provide a space for the latch engaging member 39 which has a portion 38 slidable on the rod 24 and adapted to project into the slot 37, (see Fig. 60 7) to hold the member 39 in the vertical position when the table top is to be attached, the member 39 projecting through a slot in the table top 35 and adapted to be engaged by a hook 40 (see Fig. 8) that is pivoted at

41 so that it may spring into and out of engagement with the member 39.

The table top 35 is provided with openings 42 that form convenient means by which the operator may insert his fingers to grasp the top in order to put it into place or remove it.

When the parts are in the position shown in Fig. 2, with the blanket around the folded top 35 and held in the receptacle, in order to open the receptacle, the operator first unlocks the latch 27, by manipulating the lock 28 (which lock may be of any approved type) and then he pulls up on the latch 27 (see Fig. 4) and rocks the member 20 to the dotted line position in Fig. 4, which causes rod 24 to disengage hooks 10 and enables the front 11 of the receptacle to be swung out, as shown in Figs. 1 and 3. As soon as the front of the receptacle has swung out, the tray 14, lying parallel with the front 11 of the receptacle, is tilted up until the hooks 17 engage the slots 13 and thus form fulcrums on which the tray can be swung to bring it to the horizontal position shown in Figs. 1 and 3, thereby enabling the hooks 10 to be projected through the slots or openings 48 and prevent the tray from moving in a horizontal plane forwardly or from left to right in Figs. 1 and 3. Then by rocking the member 20 to the normal position, the pins 31 are projected into the holes 34, thus holding the tray from tilting down into the receptacle again. In order to hold the latch 20 from being rocked on its pivot, the table top is opened up and put into place with one edge of the top introduced between the 95 hinged member 47 and flange 9 where it is preferably held by the resiliency of the member 9 imparting retaining friction. The outer end of the table top 35 is then fastened, as shown in Figs. 5 and 8, thus holding the member 20 against pivotal action and forming a very rigid table structure. The blanket 50 may then be used as a table cover, if desired.

In order to close up the receptacle again, 110 these operations are reversed, i. e., the latch 40 is released from the member 39, top 5 lifted off, folded up, wrapped in the blanket 50 and placed in the tray 14; after which, the operator, by grasping latch 27, rocks the 115 member 20—21 to the dotted line position shown in Fig. 3, which releases pins 31 from the holes 34 and enables the tray to be tilted on its fulcrum until the bottom of the tray engages the wall 11 when it may be slid 120 down until the end wall 15 of the tray is again in juxtaposition to the wall 3 of the receptacle. Then by closing the front 11 toward the back of the receptacle, the parts are returned to the position shown in Fig. 125 6 and the member 20—21 rocked back to its normal position and the latch 27 reintroduced into the lock 28 and secured.

From the foregoing description, taken in connection with the accompanying drawings, it is thought the complete construction, operation and advantages of my invention will 5 be readily understood by those skilled in the art.

What I claim is:—

1. A receptacle comprising a fixed back section and a front section hinged thereto 10 to open outwardly and form a support, means limiting the outward movement of the said front section, a tray slideable in the front section and adapted to be inclosed in the receptacle when the same is shut, means 15 to hold said tray horizontal in position with relation to said receptacle when the same is opened, said means including locking pins carried by the tray and adapted to engage with the receptacle.
- 20 2. A receptacle comprising a fixed back section and a front section hinged thereto to open outwardly and form a support, means limiting the outward movement of the said front section, a tray slideable in the front section and adapted to be inclosed in the receptacle when the same is shut, means to hold said tray horizontal in position with relation to said receptacle when the same is opened, said means including locking pins 25 carried by the tray and adapted to engage with the receptacle, and means for holding said pins against withdrawal when the tray is in its horizontal position.
- 30 3. A receptacle comprising a fixed member and a movable member hinged thereto at the bottom and adapted to open outward to form a support, a limiting brace for said movable member, a tray slideably engaging in said movable member, hooks carried by 35 said tray to engage with said movable receptacle member whereby said tray may swing on said member as a fulcrum when said hooks engage said movable receptacle member to limit the withdrawal movement 40 of said tray, latch pins to secure the tray horizontally, latch pin operating devices including a hinged receptacle-cap forming member on said tray.
4. A receptacle comprising a fixed member 50 and a movable member hinged thereto at the bottom and adapted to open outward to form a support, a limiting brace for said movable member, a tray slideably engaging in said movable member, hooks carried by 55 said tray to engage with said movable receptacle member whereby said tray may swing on said member as a fulcrum when said hooks engage said movable receptacle member to limit the withdrawal movement 60 of said tray, latch pins to secure the tray horizontally, latch pin operating devices including a hinged receptacle-cap forming member on said tray, and means for holding said hinged cap forming member against

movement when the tray is horizontally disposed. 65

5. A receptacle comprising a fixed member and a movable member hinged thereto at the bottom and adapted to open outward to form a support, a limiting brace for said 70 movable member, a tray slideably engaging in said movable member, hooks carried by said tray to engage with said movable receptacle member whereby said tray may swing on said member as a fulcrum when 75 said hooks engage said movable receptacle member to limit the withdrawal movement of said tray, latch pins to secure the tray horizontally, latch pin operating devices including a hinged receptacle-cap-forming 80 member on said tray, means for holding said hinged cap forming member against movement when the tray is horizontally disposed, said means comprising a top held on said tray and engaging with the tray and fixed 85 receptacle member, and a device on said cap forming member engaging with the top whereby movement of said cap forming member on its hinged axis is restrained.

6. A receptacle comprising a fixed member and a movable member hinged thereto at the bottom and adapted to open outward to form a support, a limiting brace for said movable member, a tray slideably engaging in said movable member, hooks carried by 90 said tray to engage with said movable receptacle member whereby said tray may swing on said member as a fulcrum when said hooks engage said movable receptacle member to limit the withdrawal movement 95 of said tray, latch pins to secure the tray horizontally, latch pin operating devices including a hinged receptacle-cap-forming member on said tray, means for holding said hinged cap forming member against movement when the tray is horizontally disposed, said means comprising a top held on 100 said tray and engaging with the tray and fixed receptacle member, a device on said cap forming member engaging with the top 105 whereby movement of said cap forming member on its hinged axis is restrained, and a locking device for holding said cap forming member against movement when the receptacle is closed. 110

7. A receptacle comprising a fixed member and a movable member hinged thereto at the bottom and adapted to open outward to form a support, a limiting brace for said movable member, a tray slideably engaging 120 in said movable member, hooks carried by said tray to engage with said movable receptacle member whereby said tray may swing on said member as a fulcrum when said hooks engage said movable receptacle 125 member to limit the withdrawal movement of said tray, latch pins to secure the tray horizontally, latch pin operating devices in-

cluding a hinged receptacle - cap - forming member on said tray, means for holding said hinged cap forming member against movement when the tray is horizontally disposed, 5 and a locking device for holding said cap forming member against movement when the receptacle is closed.

8. A receptacle comprising a fixed member and a hinged member and limiting 10 braces connecting said members to limit the opening movement of the hinged member, a tray having a hinged end, said tray being 15 slideable in said hinged member of the receptacle, said hinged end comprising a cap for the receptacle when closed, a top stop for engaging the inner end of said tray when the receptacle is opened and the tray is partially withdrawn and tilted, a pin to effect 20 connection between said tray and said fixed member when said tray is in the horizontal position, a member for connecting the tray with said hinged member of the receptacle when said tray is in the extended position, substantially as shown and for the purposes 25 specified.

9. A receptacle comprising a fixed member and a hinged member and limiting 30 braces connecting said members to limit the opening movement of the hinged member, a tray having a hinged end, said tray being 35 slideable in said hinged member of the receptacle, said hinged end forming a cap for the receptacle when closed, a top stop for engaging the inner end of the tray when the receptacle is opened and the tray is partially 40 withdrawn and tilted, a latch pin to effect engagement between said tray and said fixed member when said tray is in the horizontal position, a member for connecting 45 the tray with said hinged member of the receptacle when said tray is in the extended position, latch pin operating connections between said latch pin and said hinged end, and a device for holding said hinged end against movement when the parts are in the closed position.

10. A receptacle comprising a fixed member and a hinged member and limiting 50 braces connecting said members to limit the opening movement of the hinged member, a tray having a hinged end, said tray being 55 slideable in said hinged member of the receptacle, said hinged end forming a cap for the receptacle when closed, a top stop for engaging the inner end of the tray when the receptacle is opened and the tray is partially 60 withdrawn and tilted, a latch pin to effect engagement between said tray and said fixed member when said tray is in the horizontal position, a member for connecting 65 the tray with said hinged member of the receptacle when said tray is in the extended position, latch pin operating connections between said latch pin and said hinged end, and a device for holding said hinged end against

movement when said receptacle is closed and the tray is contained therein, said device comprising a finger latch on said hinged end and a lock coöperating therewith on said hinged receptacle member. 70

11. A receptacle comprising a fixed member and a hinged member and limiting 75 braces connecting said members to limit the opening movement of the hinged member, a tray having a hinged end, said tray being 80 slideable in said hinged member of the receptacle, said hinged end comprising a cap for the receptacle when closed, a top stop for engaging the inner end of said tray when the receptacle is opened and the tray is withdrawn and tilted, a latch pin to effect 85 engagement between said tray and said fixed member when said tray is in the horizontal position, a member for connecting the tray with said hinged member of the receptacle when said tray is in the extended position, latch pin operating connections between said latch pin and said hinged end, a device for holding said hinged end against 90 movement when said tray is in the horizontal position, said device comprising a top sustained on said tray, one part of said top being in engagement with said fixed member, and a connection between said top and said hinged end of said tray. 95

12. A receptacle comprising a fixed member and a hinged member and braces connecting said members to limit the opening movement of the hinged member, a tray having a hinged end, said tray being 100 slideable in said hinged member of the receptacle, said hinged end comprising a cap for the receptacle when closed, a top stop for engaging the inner end of the tray when the receptacle is opened and the tray is partially withdrawn and tilted, a latch pin for latching the tray to the fixed member when the receptacle is opened and the tray is in the horizontal position, a member for connecting the tray with said hinged member of the receptacle when said tray is in the extended position, latch pin operating connections between said latch pin and said hinged end, devices for holding said hinged end against movement when the parts are 105 in the closed position, said devices comprising a finger latch on said hinged end and a lock coöperating therewith on said hinged receptacle member, a top adapted to be sustained on said tray when said receptacle is opened and said tray is in a horizontal position, and means for securing said top rigidly to said hinged tray end. 110

13. A receptacle including a fixed back section, a front section hinged thereto to 115 open outwardly, limiting braces connecting said section, the fixed section having a top flange, a body slideable within said hinged section and adapted to be inclosed between 120 said fixed and hinged sections when the re- 125

- ceptacle is closed, said body having an end adapted to serve as a cap for said receptacle when the receptacle is closed, members for effecting engagement between said body and the hinged section when the tray is partially withdrawn, and means for holding said body horizontally when supported by said hinged section and in engagement with said top flange.
- 10 14. A receptacle including a fixed back section and a front section, a hinged connection between the said sections at the bottom, limiting braces connecting the sections, the fixed section having a top flange, a tray 15 slidable in the front section and adapted to be extended and swung into a horizontal position when the front section is opened, a member on said tray adapted to form a cap for said receptacle when the same is closed and a locking device on said front section 20 and cap member to lock the tray down in the front section and devices coöoperative with the cap member and the receptacle for holding the receptacle closed when the lock is 25 locked.
15. A device of the character described comprising a receptacle consisting of a fixed back member having bottom and side flanges and a top flange, a front member hinged to the bottom flange of said back member, said front member including side flanges to fit within those of the back member, brace members connecting the front and back members to limit the opening movement of the front member, a tray slidably engaged 30 with the front member, said front member having a slot near its free end, a hook carried by said tray to coöperate with said slot to limit the withdrawal movement of the tray and cause it to fulcrum on said front member as said tray is swung to the horizontal position, said tray adapted to engage the top flange of said fixed receptacle member, a hook beneath said fixed top member for engaging the tray to prevent separation of the tray from the back member, latch devices 35 for holding the tray against movement on said front member as an axis, latch operating devices including a hinged member on the tray adapted to be manipulated by the operator, and locking devices for holding said hinged operating member from action.
17. A device of the character described comprising a receptacle consisting of a fixed back member having bottom and side flanges and a top flange, a front member hinged to the bottom flange of said back member, said front member including side flanges to fit within those of the back member, brace members connecting the front and back members to limit the opening movement of the front member, a tray slidably engaged with the front member, said front member having a slot near its free end, a hook carried by said tray to coöperate with said slot to limit the withdrawal movement of the tray and cause it to fulcrum on said front member as said tray is swung to the horizontal position, said tray adapted to engage the top flange of said fixed receptacle member, a hook beneath said fixed top member for engaging the tray to prevent separation of the tray from the back member, latch devices 40 for holding the tray against movement on said front member as an axis, latch operating devices including a hinged member on the tray adapted to be manipulated by the operator, a foldable top adapted to be sustained on said tray and in engagement with said top flange of the back receptacle member, and means for rigidly connecting said top with said hinged latch operating member when the tray is in the horizontal 45 position, said top adapted to be folded into said tray when not in use as a top, and a sound deadening means in which said top is wrapped while locked in said tray.
16. A device of the character described comprising a receptacle consisting of a fixed back member having bottom and side flanges and a top flange, a front member hinged to the bottom flange of said back member, said front member including side flanges to fit within those of the back member, brace

ASHER O. SINKS.
